UNITED STATES PATENT OFFICE.

CHARLES ARTHUR SPEAKMAN, OF NEW YORK, N. Y., ASSIGNOR TO THE AMERICAN LITHOGRAPHIC COMPANY, OF SAME PLACE.

DESIGN FOR AN ORNAMENTAL PRINT OR PATTERN FOR CIGAR-BOXES.

SPECIFICATION forming part of Design No. 28,257, dated February 8, 1898.

Application filed November 18, 1897. Serial No. 659,044. Term of patent 7 years.

To all whom it may concern:

Be it known that I, CHARLES ARTHUR SPEAKMAN, a citizen of the United States, residing at New York, in the county of New 5 York and State of New York, have invented and produced a new and original Design for an Ornamental Print or Pattern for Cigar-Boxes, of which the following is a specification, reference being had to the accompanying drawing, forming a part thereof.

My design is intended for the ornamentation of a cigar-box.

In the accompanying drawing, forming a part of this specification, my design is shown 15 on the lid or cover of a cigar-box, the view being a front elevation of a cigar-box with the lid raised.

The design comprises a central oblong panel A, arranged diagonally across the design, having an ornamented border, an upper oblong

panel B, arranged horizontally above the central panel, and a five-pointed star D, arranged between the panels A and B.

The central panel is shown as suspended by lacing-cords at each end to staffs having 25 fleur-de-lis heads. The landscape view represents a tropical country and shows a harbor having a fort upon each side of its entrance, with the sun rising between. The star is ornamented by a tobacco-plant, and 30 between each of its points is arranged a fleur-de-lis.

I claim—

The design for an ornamental print or pattern for cigar-boxes, substantially as shown 35 and described.

C. ARTHUR SPEAKMAN.
